UNITED STATES PATENT OFFICE.

LORENZO D. WOODMANSEE, OF HAMILTON, OHIO.

IMPROVEMENT IN LEATHER PERFORATING MACHINERY FOR HARNESS MAKERS.

Specification forming part of Letters Patent No. **145,543**, dated December 16, 1873; application filed June 30, 1873.

To all whom it may concern:

Be it known that I, LORENZO D. WOODMANSEE, of Hamilton, in the county of Butler and State of Ohio, have invented a new and useful Improvement in Machines for Perforating Leather and other materials for sewing; and I do hereby declare that the following is a full and exact description thereof, reference being had to the accompanying drawings and to the letters of reference marked thereon.

My invention is especially adapted for use by harness-makers, to relieve the labor and facilitate the work of sewing; and it consists of the arrangement of an elongated stock or gate, which is provided with a row of awls, in combination with a frame, lever, and a guide for the work, as hereinafter described.

Figure 1 represents a vertical section of my perforating-machine. Fig. 2 is a front elevation of the same, with a portion of the frame broken away to exhibit the interior construction.

The frame, which may be made of cast-iron, is rectangular, and has an open front and top. The awl stock or gate B is provided with the row of awls *a*, and has the hole *C* made through it for the hand-lever *D* to freely work in. Grooves are formed on the opposite inner sides of the frame *A* to guide the gate *B* in its vertically-reciprocating motion. The bottom of the frame is perforated with holes *b b*, corresponding with the row of awls *a*, and a feed-passage, *P*, is made through the bottom of the frame, intersecting the holes *b b*, in which passage the work to be perforated is to be placed and adjusted. A suitable opening, *X*, is made through the rear side of the frame for the end of the lever *D*, by which the awl-stock is raised and depressed by the hand of the workman.

The feed-passage *P* may be provided with adjustable sides, so that it can be contracted and expanded by the use of set-screws, so as to guide work of various widths.

Leather, such as is cut into strips for traces, tugs, &c., for harnesses, may be placed in the passage *P* and perforated, preparatory to sewing by hand.

The stock *B* is caused to move up and down by means of hand-lever *D*, and the awls, which are arranged in line with the feed-passage *P*, will be thrust through the leather placed therein; and, at each upward movement of the stock and awls, the latter will be withdrawn, and the leather will be fed through the passage a sufficient distance to repeat the operation.

The perforations will be uniformly made, and the stitching can be done rapidly and neatly.

It is apparent that a series of awl-stocks having different sizes of awls, spaced for fine or coarser work, may be used interchangeably in the same frame.

I claim as my invention—

In a leather-perforating machine, the arrangement of the reciprocating stock *B*, provided with a series of awls, and a guide, *P*, within the frame *A*, the bottom of said frame being provided with holes *b b*, substantially as shown, for the purpose described.

Witness my hand this 7th day of June, A. D. 1873.

L. D. WOODMANSEE.

Witnesses:

H. P. K. PECK,
JOHN M. DAVIDSON.
